UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

ESCAPEMENT AND TRANSFER MECHANISM.

1,286,469.

Specification of Letters Patent.

Patented Dec. 3, 1918.

Application filed May 8, 1917. Serial No. 167,244.

To all whom it may concern:

Be it known that I, RICHARD LESTER WILCOX, a citizen of the United States, residing at Waterbury, in the county of New Haven and State of Connecticut, have invented certain new and useful Improvements in Escapement and Transfer Mechanism, of which the following is a specification, reference being had therein to the accompanying drawings.

This invention relates to escapement and transfer mechanism, of the type designed to receive a single blank from a conveying mechanism and to transfer it therefrom to operating tools.

It is the object of this invention, among other things, to provide mechanism of this character that will insure the receipt and transfer of a single article at a time and composed of parts of such design and structure as to be economically constructed, readily assembled and will operate with accuracy and efficiency.

To these, and other ends, my invention consists in the escapement and transfer mechanism, having certain details of construction and combinations of parts, as will be hereinafter described and more particularly pointed out in the claims.

Referring to the drawings, in which like numerals of reference designate like parts in the several figures;

Figure 1 is a plan view of my improved transfer mechanism, associated with one form of operating tools, with which it is adapted to work in harmony;

Fig. 2 is a plan view of one form of the escapement tongs, with the mechanism adjacent thereto;

Fig. 3 is a similar view of another form of escapement tongs;

Fig. 4 is a side elevation of my improved escapement mechanism with the parts in section, when taken longitudinally through the escapement tongs;

Fig. 5 is a front view thereof; and

Figs. 6, 7 and 8 are elevations of various forms of blanks that may be successfully operated upon in my improved device, Fig. 6 being a cylindrical shell, Fig. 7 a solid cylinder and Fig. 8 a cone.

As shown in the drawings my escapement

and transfer mechanism is designed to operate upon blanks that are cylindrical in form, either solid or a shell as illustrated in Figs. 6 and 7 of the drawings, and blanks of irregular form, such as a cone, as illustrated in Fig. 8. These blanks are shown as illustrations of some of the forms of articles that can be successfully operated upon with my improved mechanism, but it is equally well adapted to operate upon articles of numberless other shapes, and I do not therefore desire to be limited to those specifically shown.

Only one of the many forms of mechanism with which my invention can be successfully associated is shown in the drawings, and consists of a bolster plate 1, having a slide 2 therein that receives a reciprocating motion in the direction of its length by mechanism not shown.

Movably mounted within the slide 2 are a plurality of spring fingers 3 that are pivotally connected at one end to said slide within the sockets 4, and have semi-circular grooves in their inner faces adjacent to the outer ends thereof which combine to form a receiving opening 5. Springs 6 that lie between the fingers 3 and the slide 2 exert a pressure so as to move the fingers inwardly. Beneath these fingers in the bolster plate 1, are a plurality of dies 7, the form and construction of which are not material to the present invention. Suffice it to say, however, that with each reciprocatory movement of the slide 2, the fingers 3 travel from one die 7 to the next die, and at the succeeding movement of the slide they return to their original position.

The specific construction and arrangement of the mechanism above described, constitutes no part of the present invention, which consists in part in mechanism for receiving, releasing and transferring blanks one by one from the conductor tubes 8 to the fingers 3 of the delivering mechanism above referred to.

Slidably mounted so as to permit setting in a particular stationary position upon the bolster plate is the bracket 11, and fixed thereon are the standards 9 and 10, the object of changing the position of said bracket being to adjust the same into a certain se-

lected position relatively to the aforesaid delivering mechanism and series of dies.

The mechanism for transferring the articles, such as shown in Figs. 6 and 7, comprises a pair of companion tongs, which are pivotally connected to the standard 10 by the pins 12, the upper of said tongs being designated by the numeral 13, and the lower by the numeral 14, between the rear ends of which are the springs 15, which normally exert their tension so as to move said tongs upon their pivot mounting and cause their inner ends, having the stop pins 16 therein, to move toward each other. These tongs are moved upon their pivot mountings against the tension of the spring 15 so as to move the pins 16 away from each other by the plunger 17, which is slidably mounted in the standard 10 and provided with a ball 18 upon its lower end, a coil spring 19 surrounding the shank thereof, and a collar 20 upon its opposite end. As the plunger 17 moves downwardly, the ball passes from the upper tongs 13 to the lower tongs 14, thereby permitting the upper tongs to close through the action of the spring 15, and the lower tongs to open, the movement of the plunger 17 in the opposite direction producing the reverse action upon the lower and upper tongs.

30 The distance between the sets of pins 16 and the upper and lower tongs is substantially the same as the length of the blank, so that only one blank at a time can rest therebetween.

35 As the irregular shape of articles such as illustrated in Fig. 8 are not of uniform diameter throughout their length it is necessary that the shape of the jaws of the lower tongs should be modified.

40 In the mechanism associated with the standard 9, such means are shown, the lower jaws designated 21 being solid instead of provided with pins 16, as are the upper jaws, and the semi-circular recesses 22 and 45 the abutting faces of said tongs combining to form an opening of substantially the same shape as the blank to be received therein.

Mounted in the bracket 11, so as to move in a path at substantially a right angle to the slide 2, are the transfer slides 23 and 24, upon which the tongs 25 are pivotally mounted through the screws 26; a spring 27 between two arms of the tongs exerts its tension so as to move the opposite ends of said tongs toward each other; a stop 28 fixed in the slide limits the inward position of one of said tongs, so that the pockets 29 in the outer ends thereof are directly below the conductor tube 8, when in its retracted position.

60 The tongs 30 are of substantially the same construction as the tongs 25, and have a pocket 31 at their outer end. Upon one of the tongs 30 is a lug 32, which in one of its

positions engages the point of a screw 33 65 threaded in the bracket 11 and when so engaged holds the tongs so that they are not entirely closed when in their rearmost positions. As the tongs 30 are designed to receive blanks cylindrical in shape, such as 70 shown in Figs. 6 and 7, it is necessary that they be gripped for transfer, and this grip is acquired through the spring 27 when the screw 33 is not in engagement with the lug 32. The coöperation of these two latter elements provides means for opening the tongs 75 slightly to release the frictional hold.

The slides 23 and 24 have a reciprocatory motion toward and away from the slide 2 by means not shown, as any form of mechanism for imparting such motion is adapted 80 for use with this apparatus.

The plunger 17 is moved downwardly through the action of a rock shaft 34 that is journaled in a fixed part 35, rock arm 36 85 fixed to said shaft having a screw 37 therein which engages the upper end of said plunger. It is apparent that the extent and timing of the movement of the plunger 17 may be varied by the change of the position of 90 the screw 37 within the rock arm 36, a jam nut 38 being provided to lock the screw in any of its adjusted positions.

Any means may be utilized for imparting a rocking movement to the arm 36, a lever 95 39 being connected therewith, through which such movement may be transmitted.

In operation the cylindrical blank passes down through the conductor tube 8 and is discharged from the lower end thereof with 100 the bottom of the blank resting upon the pins 16 in the lower tongs 14, the plunger 17 then moving downwardly and permitting the upper tongs 13 to close and the pins 105 therein to pass under the next upper blank in the column of blanks within the conductor tubes, at the same time opening the lower tongs 14 so that the pins 16 therein pass from under the blank, which then drops by gravity into the pocket 31 in the tongs 30. 110 The slide 23 then moves forward until the pocket 31 registers with the openings 5 in the pair of spring fingers 3, directly in front thereof, at which time it is ready to be forced out of said tongs by the punch mechanism, (not shown) and not forming part 115 of the present invention. The slide 23 is then withdrawn and the above described operations are repeated.

As the vertical distance between the pins 16 between the lower and upper tongs is substantially the same as the blank, it is apparent that only one blank can escape from the conductor tube at a time, the pins 16 in the lower tongs forming a rest for the bottom of the blank in the column, and when they move away from each other, the pins 16 in the upper pair of tongs prevent the

escape of another blank until the tongs 14 are again moved together and the pins 16 therein form a stop for the next blank. As soon as the forward movement of the slide 5 23 begins the lug 32 passes beyond the point of the fixed screw 33 and the spring 27 moves one of the arms of the tongs 30 so as to grip the blank. It is apparent that the pocket 31 is therefore slightly larger in 10 diameter when the jacket drops therein than after the forward movement of the slide begins.

Blanks of irregular form, such as shown in Fig. 8, are delivered into the pockets 29 15 of the tongs 25 in substantially the same manner as above described, and the slide 24 moves forward in substantially the same manner as the slide 23.

There are minor changes and alterations 20 that can be made in my invention, aside from those suggested, and I would therefore have it understood, that I do not limit myself to the exact construction herein shown and described, but claim all that falls fairly 25 within the spirit and scope of the appended claims.

Having described my invention, what I claim as new and desire to secure by Letters Patent, is:—

30 1. In a mechanism of the class described; blank feed checking means; blank receiving means; and blank conveying means mounted upon a base movable in relation to said blank feed checking means whereby said blank conveying means is alternately brought into juxtaposition with said blank feed checking means and said blank receiving means.

35 2. In a mechanism for feeding and conveying blanks; feed checking tongs and conveying tongs, the latter being mounted on a base movable in relation to said feed checking tongs, whereby blanks taken from said feed checking tongs are delivered at a distant point.

40 3. In a mechanism for feeding and conveying blanks from a source of supply to a selected point; a plurality of feed checking tongs; blank conveying means mounted upon a base movable in relation to said feed checking tongs; and a plurality of blank receiving devices provided on a base movable independently relative to said conveying means.

45 4. In combination; means for conveying blanks to a delivery station; means for permitting the escape at said delivery station of only one of said blanks at a time, said means comprising a plurality of tongs; and a member substantially globular in form 50 mounted so as to be movable between said pairs of tongs and by its successive engagement with said pairs of tongs opening the same.

55 5. In a mechanism of the class described,

the combination of a feed checking means, 60 and a blank conveying means, each of said means comprising a plurality of tong-like devices and having means associated therewith for bringing them into operative relation with each other in a selected order. 70

6. In a mechanism of the class described, a plurality of self-closing, tong-like devices for controlling the feed of a blank from a column of blanks, means for positively and alternately opening said devices, and conveyer tong-like devices mounted upon a movable base and to which conveyer devices the blank is delivered from said feed controlling devices and by said conveyer devices delivered to a distant point. 75

7. In a mechanism of the class described, feed checking means and blank conveying means, each means comprising a plurality of levers of the same class constituting tong-like devices, and positive means for alternately opening said tong-like devices. 80

8. In a mechanism of the class described, feed-checking and blank-conveying means, each means comprising a plurality of levers of the same class constituting tong-like, feed-checking devices, and a member movable between said feed-checking devices for alternately opening the same. 90

9. In an escapement and transferring mechanism as described, a plurality of tong-like, feed-controlling devices mounted upon a supporting member, means for alternately opening said devices and a blank transferring tong-like device mounted upon a member movable independently relative to 100 said supporting member. 95

10. In an escapement and transferring mechanism as described, the combination of a plurality of tong-like, feed-controlling devices mounted upon a supporting member, means for alternately opening said devices, a blank-conveying, tong-like device mounted upon a member movable independently of said supporting member, and a series of delivering tong-like devices so mounted that any selected one can be positioned in line with said conveying device. 105

11. In a mechanism of the class described; feed - checking means; conveyer means mounted upon a base movable in relation to said feed-checking means, and both means comprising a plurality of self-closing tong-like devices; a spreader between said devices acting to engage and open the same; and adjustable means for gaging and determining the movement of said spreader. 110 115

12. In a mechanism for feeding blanks, a feed-checking device having pivoted arms or members opened alternately at predetermined times, a spreader for effecting the opening movement of said arms or members, a blank transferring device and a movable support therefor comprising a sliding 120 125

member which in one position is brought into operative relation with said checking device.

13. In a mechanism for feeding blanks,
5 the combination of a plurality of tong-like, feed-checking devices, and a tong-like device which delivers a blank to one of a series of

dies and all of said devices being operatively associated so as to operate in timed relation with each other.

In testimony whereof I have hereunto affixed my signature.

RICHARD LESTER WILCOX.
